FIG. 2.

INVENTOR
DONALD D. MAXWELL

BY
Edward R. Inman
ATTORNEY

UNITED STATES PATENT OFFICE

106,240

DESIGN FOR A DISPLAY RACK OR SIMILAR ARTICLE

Donald D. Maxwell, Oil City, Pa.

Application December 5, 1936, Serial No. 66,341

Term of patent 14 years

To all whom it may concern:

Be it known that I, Donald D. Maxwell, a citizen of the United States residing at Oil City, in the county of Venango and State of Pennsylvania, have invented a new, original, and ornamental Design for a Display Rack or Similar Article, of which the following is a specification, reference being had to the accompanying drawing, forming a part thereof.

I claim the following:

The ornamental design for a display rack or similar article, substantially as shown.

DONALD D. MAXWELL.
